UNITED STATES PATENT OFFICE.

SAMUEL C. BROWN, OF NIAGARA, OREGON.

CAR-COUPING.

SPECIFICATION forming part of Letters Patent No. 511,117, dated December 19, 1893.

Application filed August 15, 1893. Serial No. 483,162. (No model.)

To all whom it may concern:

Be it known that I, SAMUEL C. BROWN, of Niagara, in the county of Marion and State of Oregon, have invented certain new and useful 5 Improvements in Car-Couplings; and I do hereby declare that the following is a full, clear, and exact description thereof, reference being had to the accompanying drawings, and to the letters of reference marked thereon, 10 which form part of this specification.

This invention is an improved car coupling especially designed for freight cars; and it consists in novel devices for securing or releasing the link in the draw head; and for adjusting the link so as to cause it to enter an 15 opposite draw-bar; and for operating the said devices from the side or top of car; all of which will be clearly understood from the following description in connection with the 20 drawings, in which—

Figure 1 is a perspective view of the parts of my invention applied to the end of a car. Fig. 2 is a perspective sectional view of the coupling, indicating the link coupled. Fig. 3 25 is a similar view showing the link in position to be locked or released.

In said drawings A represents a draw-bar in the throat of which about center thereof and near its front end, is secured a beveled 30 catch block B which has a screw threaded shank b depending through a slot in the floor of the draw bar and secured by a nut b' as shown. The block may be seated in a recess in the floor of draw bar and abuts against a 35 lug a on the floor, which is beveled on its front face as shown, so that a link striking on said lug will ride up thereon onto and over block B, dropping over the latter in the position indicated in Fig. 2.

C designates a vertically movable link-adjusting bar playing in guide slots in the top and bottom of the draw bar in rear of block B, and having a forwardly projecting arm c opposite block B adapted to underlie the end 45 of the link as indicated in the drawings, and above arm c it is provided with two parallel arms c' adapted to overlie the end of the link as indicated in Figs. 2 and 3. When the bar C is down the arms c' will prevent the link 50 being raised or disengaged from block B, unless bar c is also raised; and when bar C is raised arm c will lift the inner end of the link

until it is freed from the block as indicated in Fig. 3 of the drawings. I provide the bar C with the arms c, c' so that the link can 55 be adjusted to facilitate its engagement with another draw-bar in coupling the three arms preventing lateral rocking of the links, but do not confine myself to a construction having 60 three arms.

As a further safeguard to prevent uncoupling of the link, I employ a tumbler D which is pivoted on a pin D' above block B as shown. The front face of tumbler D is beveled inwardly and downwardly to its point of contact with block B, and its rear face is vertical and in line with the rear face of block B, so that should the link rise over the block it will be held by the tumbler as will be apparent from Fig. 2 of the drawings. The meeting faces of the tumbler and block are also beveled upwardly and outwardly as at b² so that outward swing of the tumbler is prevented though it is free to swing inward and the tumbler is rounded as at D² around the 75 opening for pivot pin D', this portion fitting into a correspondingly rounded recess A' of the draw-bar, so that draft strain on the tumbler will be transferred direct to the draw-bar and it will be impossible to pull the 80 block or tumbler out without breaking away the walls of the draw bar. Outward swing of the tumbler is further prevented by a squared shoulder D³ between the upper end of the front face and portion D² thereof 85 which abuts against a shoulder A³ on the draw bar when the tumbler is down. The tumbler is provided with a rearwardly extending arm d lying above arms c of bar C, and pivotally connected to the upper ends of 90 bars E, E, which are arranged at each side of bar C and are vertically movable independently thereof. The lower ends of bars E are connected below the draw bar by a cross plate e. By pushing plate e upward bars E, 95 E, are lifted, and thereby turn the tumbler on its pivot and out of engagement with block B as indicated in Fig. 3, and when the bars E, E, are partly lifted, plate e strikes the bottom of bar C and raises the latter, so that the 100 link will be lifted after the tumbler is turned out of the way as indicated in Fig. 3.

The draw bar is chambered as at A² to accommodate the moving parts, and access can

be had thereto through the top of the draw bar, but the chamber is closed by a cap piece F as shown so that rain or dirt are kept out of the draw bar. This cap may be provided with a slot f to receive and guide the upper end of bar C.

G designates a shaft suspended transversely below the draw bar and journaled in hangers H, H, of any suitable construction. 15 This shaft is provided with a crank arm g, underlying and adapted to contact and raise plate e when the shaft is properly turned as can be done by a handle G' on either end, which handle can be locked by means of a spring catch h so as to hold plate e raised, and the coupler in uncoupled position as indicated in Fig. 3. The shaft may be also rotated from the top of the car by means of a pull rod or chain I, the lower end of which is connected 20 to a crank arm on the shaft G as shown in Fig. 1.

My improved coupling permits the desired amount of slack between two coupled draw-heads necessary in starting heavy trains; it 25 cannot become casually uncoupled; and the coupling or uncoupling, and adjusting of the link, can be effected from either side or top of car.

Having described my invention, what I 30 claim as new, and desire to secure by Letters Patent thereon, is—

1. The combination of the draw-bar having a link holding block or lug in its throat, with a vertically movable bar in said draw-bar and 35 depending therethrough behind said block provided with the upper and lower forwardly projecting arms adapted to embrace the end of an incoming link and hold the link upon the block when the bar is down or raise it to 40 disengage the block when the bar is raised, and means for lifting said bar at its lower end, substantially as described.

2. The combination of the draw bar the 45 link locking tumbler pivoted in the throat thereof, and the vertically movable bars pivotally connected to said tumbler and depending below the bar, and means for raising said bars so as to swing the tumbler, substantially as described.

3. The combination of the draw bar having a link holding block or lug in its throat, with a vertically movable bar in said draw bar behind said block provided with upper and 55 lower forwardly projecting arms adapted to embrace the end of an incoming link, and hold the link upon the block when the bar is down, or raise it to disengage the block when the bar is raised, and a locking tumbler pivoted in the draw bar above said block and co- 60 acting therewith, substantially as and for the purpose described.

4. The combination of the draw-bar having a link holding block or lug in its throat, with a vertically movable bar in said draw bar behind said block provided with upper and lower forwardly projecting arms adapted to embrace the end of an incoming link, and hold the link upon the block when the bar is down, or raise it to disengage the block when the bar is raised, and a locking tumbler pivoted in the draw bar above said block and coacting therewith, and means for swinging said tumbler out of the way prior to the lifting of the link by said bars, substantially as described.

5. The combination of the draw bar, the link retaining block therein, the link adjusting bar, the tumbler pivoted in the draw bar above said block, the vertically movable bars for operating said tumbler, and means substantially as described, whereby the latter bars are caused to raise the link adjusting bar after they have moved the tumbler out of the way of the link, substantially as described.

6. The combination of the draw bar having a link locking lug or block as B, a pivoted link locking tumbler as D, and means for moving said tumbler out of the way and simultaneously lifting the link above the lug, substantially as described.

7. The combination of the draw-bar A, the lug or block B therein, the bar C having arms c, c', the tumbler D and the bars E, all constructed and arranged to operate substantially as and for the purpose specified.

8. The combination of the draw bar, the tumbler D, the vertically movable bars E connected to said tumbler, and the rock shaft and its crank arm for raising said bars, and means for rocking said shaft, substantially as described.

9. The combination of the draw bar, the link retaining block therein, the link adjusting bar, the tumbler pivoted in the draw bar above said block, the vertically movable bars for operating said tumbler, and means substantially as described whereby the latter bars are caused to raise the link adjusting bar after they have moved the tumbler out of the way of the link, and the rock shaft, its 105 crank arms, and means for rocking said shaft so as to raise said vertically movable bars, all constructed and arranged substantially, as described.

In testimony that I claim the foregoing as 115 my own I affix my signature in presence of two witnesses.

SAMUEL C. BROWN.
